UNITED STATES PATENT OFFICE.

EDWARD C. HOLMES, OF CINCINNATI, OHIO.

MOLDING MACHINE.

Application filed May 9, 1925. Serial No. 29,211.

My invention relates to molding machines in general and particularly to improvements in molding machines which will provide means for forming a plurality of spirally fluted patterns within the mold, which are particularly adapted for molding spirally grooved spikes.

It is the object of my invention to provide mechanism to be inserted in a molding machine enabling a plurality of spirally fluted patterns to be insertable within a mold with the necessary twisting motion which will combine the correct longitudinal and rotative motion so that the patterns formed in the molding sand within the flasks of the machine will correspond with the spirally fluted patterns which are inserted, so that screw threaded spikes can be made very economically in quantity production. Furthermore it is my object to withdraw the patterns with the necessary receding motion which will not spoil the pitch of the spirally fluted impressions in the molding sand. It is further my object to provide a means for molding a plurality of spirally fluted spikes by a simple device which may be inserted on any standard molding machine.

Referring to the drawings:

Figure 1 is a side elevation, partly diagrammatic, showing a standard molding machine with the position of my structure which enables me to accomplish the above objects indicated in dotted lines.

Figure 2 is a sectional view of the inner construction of the machine as modified in my invention.

Generally indicated at 1 is the supporting base of a type of molding machine in combination with which I have illustrated my invention; to which are secured the bosses 2 in which are pivotally mounted the arms 3 which support the head 4. The head slidably retains rods which support the top die 4^a which is usually movable with a compressed air cylinder as indicated at 5. In ordinary practice the molding table shown at 6 has a flat table like top 6^a on which the flask, indicated at 7 is placed and filled with molding sand. The patterns in ordinary practice are then placed in the molding sand and the top head swung into position and lowered to press the molding sand securely about the pattern. The head is then released and the flask withdrawn from the patterns and taken to the pouring room where the molten metal is poured into the

mold to fill up the impressions left by the pattern.

Heretofore, it has been almost impossible to secure a good mold of a threaded or spirally fluted article it often being necessary to insert a mold by hand giving it the necessary twisting motion to make the spiral grooves of the pattern leave the proper pitch in the impression within the molding sand.

Under the table I have provided a housing 8 which carries a plurality of patterns 9 which in the illustration shown are for forming impressions of spirally fluted spikes. The lower ends of these patterns are rotatively mounted in a plate 10 which forms a part of the housing. The housing may be raised and lowered by rack bars 11 which extend through bearings 12 in the frame of the machine. These rack bars mesh with gears 13 which are rotated by a centrally located gear 14 which is mounted on a shaft 15, and a spring handle 16 is secured on this shaft and by lifting up on the handle the gears are turned and the rack bars moved upwardly. The limit of movement of the spring handle is determined by a slot 17 in an arcuate plate 18 retained in the frame of the machine which the handle bears against when it is moved toward the limit of its upward movement. When the handle is raised to a position opposite the slot it springs into it and thus the upward movement of the housing is determined.

Horizontally disposed and rigidly retained within the frame of the machine is a plate 19 with holes adapted to admit the plurality of patterns in their upward movement, and bearings within the holes slidably retain the patterns. Pins 20 projecting from these bearings extend within the threads of the patterns and as the patterns are moved upwardly with the raising of the handle, the patterns are turned rotatively which results in the impressions of the patterns within the molding sand having the same pitch as the patterns.

By regulating the position of the slot 17 which can be done by movement of the plate 18 into a different series of holes 21 in the frame, spikes of desired length can be made. The particular spikes which it is my desire to manufacture have an extended head which I mold by placing the head patterns 22 in the table top 6^a through which the threaded patterns pass as they are raised into the molding sand. These head patterns are hol-

low to admit the fluted patterns of the shanks of the spikes so that when the impressions in the sand are completed the spikes may be molded, or they may be combined 5 with complementary impressions prepared in another flask in order to produce square headed spikes as required to form spikes in accordance with my Patent #1,294,268 of February 11, 1919.

10 Having thus described my invention, what I claim as new and desire to secure by Letters Patent, is:

1. In combination with a molding machine, a movable top head element and a stationary bottom table element with apertures 15 in the table element and a housing element outside the table element with means for reciprocatingly moving the housing element with relation to the table element, spirally fluted patterns rotatively mounted within the housing element, and a stationary element with projecting elements adapted to project within the flutes of the patterns, and means for moving the housing element, and the spirally fluted patterns adapted to form female impressions in a mold on the table top.

2. In combination with a molding ma-

chine, a movable top head element and a stationary bottom table element with apertures 30 in the table element and a housing element outside the table element with means for reciprocatingly moving the housing element with relation to the table element, spirally fluted patterns rotatively mounted within the housing element, and a stationary element with projecting elements adapted to project within the flutes of the patterns, and means for moving the housing element, and the spirally fluted patterns adapted to form female impressions in a mold on the table 40 top, and head patterns adapted to be disposed in the apertures to form heads for the spirally fluted impressions.

3. In combination with a molding machine, a plurality of patterns comprising tubular shafts, having spirally disposed grooves therein, and having spirally disposed guide ways to impart rotary movement with the withdrawal of said patterns from a mold, said grooves and guideways being disposed on said shafts in similar spiral direction with relation to the axes of said shafts.

EDWARD C. HOLMES.
